MODULATOR CIRCUIT

James R. Moore, Dutch Neck, N.J.

Application July 22, 1943, Serial No. 495,718

7 Claims. (Cl. 250—27)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to electron tube modulating networks, particularly the application of such networks for pulse modulating the transmitter of pulse-echo object detection equipment.

The tubes of such transmitters are usually maintained at cutoff by a high negative bias impressed upon the grids or insufficient potential on the plates. Sharp positive pulses of high peak power, developed in a modulator, are impressed on said grids, to overcome said bias, or on said plates to raise their potential, so that the transmitter oscillates for the duration of said pulses. Such oscillating periods are of relatively short duration separated by intervals of considerably longer duration.

It is an object of this invention to provide an improved modulator for the abovementioned purpose. More particularly, it is an object of the invention to provide a modulator which consumes a substantial amount of power only while the transmitter is being pulsed. This permits development of high peak power while the average power dissipated is maintained at a relatively low level.

For this purpose a portion of the impedance in the output circuit of the modulator tube consists of an electronic impedance which is varied simultaneously with, and in opposite sense as, the impedance of the modulator tube.

For a better understanding of the invention, together with other and further objects thereof, reference is had to the following description taken in connection with the accompanying drawing, and its scope will be pointed out in the accompanying claims.

Referring to the drawing, which shows a schematic circuit of my invention, tubes 10 and 12 are part of a conventional transmitter oscillator, the usual plate potential sources and tuning and coupling elements being omitted. Said tubes are normally blocked by means of a negative potential impressed upon the grids thereof from a potential source 13, through a high resistance 14. Said tubes are adapted to be intermittently unblocked by means of sharp positive pulses of voltage impressed upon the grids in such direction as to overcome said negative bias, so that the oscillator functions for the duration of said pulses.

The pulses are derived from the output circuit of a modulator network comprising two tubes 15

and 16 having their space current paths connected in series with a resistor 17 and a source of high potential B voltage 18. Tube 16 is also connected to a second source of B voltage 19 in series with a diode 20 and resistor 17. Source 19 is of considerably lower voltage than source 18. A high value resistance 22 is shunted across the grid and cathode of tube 16. Terminal 23 is adapted to be connected to a source of intermittently generated negative-going pulses of short duration, spaced at intervals of considerably longer duration.

The above described circuit operates as follows: Since there is no grid bias impressed on tube 16, said tube is normally conducting and a current flows from source 19, through diode 20, resistor 17, the anode-cathode path of tube 16, and then back to the source through ground.

The voltage drop across resistor 17 biases the grid of tube 15 negatively with respect to its cathode so that said tube operates at or below plate current cutoff and no current can flow therethrough from source 18. Under these conditions tube 15 constitutes, in effect, a load of substantially infinite impedance in the anode circuit of tube 16, so that no power is dissipated from source 18.

The grid of tube 16 is intermittently rendered negative by means of sharp negative-going pulses impressed thereon from terminal 23, through a blocking condenser 24, of low impedance to the pulse components. Each negative-going pulse blocks tube 16 so that the current through resistor 17 is reduced to zero. The blocking bias on the grid of tube 15 is therefore removed and the impedance of said tube is suddenly reduced to a relatively low value.

This causes the potential at the cathode of tube 15 to rise to substantially the potential of the anode of said tube and a sudden surge of current takes place from source 18, through tube 15, blocking condenser 24, of low impedance to the pulse voltage, and resistance 16 to ground. The direction of this current is such as to bias the grids of the oscillator tubes highly positive in opposition to the negative bias of source 13. Diode 20 prevents dissipation of this voltage to ground. As a result, the oscillator grids are rendered sufficiently positive to permit the oscillator to generate high frequency oscillations for the duration of each pulse. The cycle of operations above described are repeated for each negative pulse applied to the grid of tube 16.

It will be seen that relatively little power is dissipated by the modulator during the intervals

between pulses, even though tube 16 is conducting. Resistor 17 is of the order of a few hundred ohms and the voltage of source 19 is small compared to the voltage of source 18, so that the power dissipated between pulse intervals is relatively low compared to the peak power developed in the circuit.

There has been described a pulse modulator network including a normally conducting tube and an electronic impedance in the plate circuit of said tube. Between pulse intervals said tube is conducting but the electronic impedance is kept substantially infinite by means of a cutoff bias voltage developed across a relatively small resistance in the conducting channel including said tube. When a sharp negative voltage is impressed on the grid of said tube, it is rendered non-conducting and the electronic impedance is at the same time reduced to a minimum thereby causing a tremendous reduction in the voltage drop thereacross. The resulting voltage is impressed in such direction on the grid circuit of the oscillator as to overcome the blocking bias thereon and permit it to generate sustained oscillations for the duration of said pulse.

If plate modulation is used, then the output of the modulator will obviously be applied to the plates of the oscillator.

The modulator network has thus far been described as applied to suppressed carrier pulse modulation. It is, however, equally applicable to continuous carrier modulation systems using other types of modulation signals, e. g. sinusoidal waves.

For this purpose, the negative grid bias on the oscillator tubes 10 and 12 is reduced to permit said tubes to oscillate continuously. Both modulator tubes 15 and 16 are normally maintained conducting by reducing the negative bias applied from resistor 17 to the grid of tube 15 so that said bias is insufficient to maintain said grid at plate current cutoff. This can be done connecting the lead from the grid of tube 15 to an intermediate point of resistor 17, rather than to the lower end thereof. Another way of accomplishing this result is to reduce the value of resistor 17, or to reduce the current therethrough by decreasing the voltage of source 19, or to apply a negative bias to the grid of tube 16, or by a combination of the above expedients.

While there has been described what is at present considered a preferred embodiment of the invention, it will be obvious to those skilled in the art that various changes and modifications may be made therein without departing from the invention, and it is, therefore, aimed in the appended claims, to cover all such changes and modifications as fall within the true spirit and scope of the invention.

I claim:

1. An electronic network comprising a pair of electron tubes having their space current paths connected in series with a source of potential, means to maintain one of said tubes conducting, means responsive to said conduction to bias the other tube to cutoff, and means responsive to a signal to render said one of said tubes non-conducting, so as to remove said cutoff bias and render said other tube conducting, whereby the relative potential drops across said tubes are altered, and an output circuit coupled to the junction of said space current paths.

2. An electron relay comprising at least first and second grid controlled electron tubes, a source of plate potential having its positive pole

connected to the anode of said first tube, and its negative pole connected to the cathode of said second tube, the cathode of said first tube being connected to the anode of said second tube, a signal input circuit for said relay connected between the grid and cathode of said second tube, a load circuit coupled to the junction of said anode and cathode, means to normally maintain said second tube conducting and said first tube non-conducting, said means including a second source of potential between the anode and cathode of said second tube, and means responsive to changes in input voltage to reverse the conducting states of said tube whereby the potential of said junction is altered.

3. An electron tube network comprising first and second electron tubes each having at least an anode, cathode and grid, an impedance having one end connected to the cathode of said first electron tube and having its other end connected to the anode of said second electron tube and the grid of said first tube, means to positively bias the anodes of said electron tubes with respect to their cathodes, means including a second source of plate potential to maintain said second tube normally conducting whereby a current flows through said impedance and said second tube, and whereby the resulting voltage drop across said impedance maintains the grid of said first tube negatively biased with respect to its cathode, and means to impress signals upon the grid of said second tube to decrease the conductivity of said second tube, whereby the drop across said impedance is decreased and the conductivity of said first tube is increased, and a load circuit responsive to said increase in conductivity.

4. An electron tube network comprising first and second electron tubes each having at least an anode, cathode and grid, an impedance having one end connected to the cathode of said first electron tube and having its other end connected to the anode of said second electron tube and the grid of said first tube, a source of plate potential connected between the anode of said first tube and the cathode of said second tube, means including a second source of plate potential to maintain said second tube normally conducting, whereby a current flows through said impedance and said second tube, and whereby the resulting voltage drop across said impedance maintains the grid of said first tube sufficiently negative to render it non-conducting, and means responsive to signals to render said second tube momentarily non-conducting, whereby the drop across said impedance is decreased, said first tube is rendered conducting and the positive potential of its cathode is increased, and means responsive to said increase in cathode potential.

5. An electron tube network comprising a diode, first and second electron tubes each having at least an anode, cathode and grid, a resistor having one end connected to the cathodes of said diode and said first electron tube and its other end connected to the anode of said second electron tube and the grid of said first tube, means to positively bias the anodes of said diode and said first electron tube with respect to the cathode of said second tube, said second tube being normally conducting whereby a current flows through said diode, said resistor, and said second tube, and whereby the resulting voltage drop across said resistor maintains the grid of said first tube sufficiently negative to render it non-conducting, and means to render said second tube

momentarily non-conducting, whereby the drop across said resistor is decreased, said first tube is rendered conducting, and the positive potential of its cathode is increased, and a load circuit responsive to said increase in cathode potential.

6. A network as set forth in claim 5, wherein said load circuit is connected across said diode.

7. A network as set forth in claim 5, wherein said load circuit is connected in series with a blocking condenser across said diode.
